Primary Examiner — Cary M Robinson*Assistant Examiner* — Emily Anna Saunders(74) Attorney, Agent, or Firm — Minder Law Group; Willy H. Wong(57) CLAIM

The ornamental design for a dog shaped bubble gun, as shown and described.

DESCRIPTION

FIG. 1 is a front view of the dog shaped bubble gun in accordance with the present invention.

FIG. 2 is a rear view thereof.

FIG. 3 is a left side view thereof.

FIG. 4 is a right side view thereof.

FIG. 5 is a top view thereof; and,

FIG. 6 is a bottom view thereof.

The broken lines in the drawings show portions of the dog shaped bubble gun and form no part of the claimed design.
